Specification of Letters Patent. Patented Oct. 19, 1920.

Application filed March 15, 1920. Serial No. 365,727.

To all whom it may concern:

Be it known that we, LOUIS H. HARTMAN, and CARL H. HARTMAN, citizens of the United States, and residents of Toledo and 5 Woodville, in the county of Lucas and county of Sandusky, respectively, and State of Ohio, have made an invention appertaining to Bag-Making Machines; and we do hereby declare the following to be a full, 10 clear, and exact description of the invention, such as will enable others skilled in the art to which it appertains to make and use the same, reference being had to the accompanying drawings, and to the characters 15 of reference marked thereon, which form a part of this specification.

Our invention relates to a means for directing the ends of opposite sides of a tubular member so that the end of the tubular member may be properly folded. In 20 bag making machinery of a type well known in the art, means is provided for making bags from paper fed continuously from a roll wherein the edges of the paper are 25 turned under a form and secured together by a cementitious material to form a tube of paper having a size the same as that of the bags and from which portions are cut transversely to make the bags of suitable 30 length. The machines have a means for folding the end of the tubular member to form one or both ends of the bags, a severing or cutting means and a feeding means to feed the tubular paper body beneath the 35 severing or cutting means. In the particular form of the machine to which the invention pertains, a means is provided for folding the forward end of the paper tube to form the bottom of each bag. By our invention is provided a means that operates 40 through the tubular member, the feeding rolls and in the vicinity of the folding means for properly directing opposite side edges of the forward ends of the paper tube 45 so that the said opposite side edges will be engaged to produce proper folding and prevent the end of the tube or the ends of the bags from being crumpled up in the folding operation. Inasmuch as the tubular member 50 is formed by uniting side edges of the sheet material, namely, the paper, with a moist cementitious material, any implement placed within the tubular member that would cause it to bulge while the edges

are being held by the cementitious material 55 while still moist, will cause a deformity in the tubular member and consequently a deformity in the bags formed therefrom. By our invention the side edges of the leading end of the tube are guided without drawing 60 the sheet material of which the bags are formed, particularly without drawing the body portion of the tube or the bags, and when the edges are separated in their guiding operations, this separation is performed 65 only under conditions that will not cause deformation.

Other features and advantages of our invention will appear in the following description and upon the examination of the 70 accompanying drawings.

Our invention may be contained in structures of different forms. To illustrate a practical application of our invention we have selected a construction containing or 75 embodying the invention and will describe it hereinafter. The particular construction selected is illustrated in the accompanying drawings.

Figure 1 is a partially broken side view 80 of a bag making machine containing the invention. Fig. 2 is a sectional view of the means for guiding the edges of the paper with reference to the folding means. Fig. 3 is a top view of a part of the device 85 illustrated in Fig. 2. Fig. 4 is a sectional view taken on the line 4-4 indicated in Fig. 1 and shows the means of operating the part illustrated in Fig. 2. Fig. 5 is a sectional view taken on the line 5-5 indicated in Fig. 1. Fig. 6 illustrates the means 90 for severing the parts that form the bag from the tubular member. Figs. 7 and 8 illustrate the operation of the device for guiding the edges of opposite sides of the portion to be formed into a bag preparatory 95 to the folding operation of the forward end of the said portion that has been or is about to be severed by the cutting means illustrated in Fig. 6. Fig. 9 illustrates the parts 100 of the machine that fold the ends of the tube or ends of severed portions that form the bag, the side edges of the bag having been guided by the said guiding means and withdrawn to prevent interference with the folding means. Fig. 10 illustrates diagrammatically the folding operation to which the paper is subjected and indicates the extent 105

to which the said guiding means is withdrawn to prevent interference with the folding means and the severing means.

1, Fig. 1, is the frame of the machine 5 selected for purposes of illustration. The driving connections between the parts is not shown it being understood that the parts are timed by suitable gearing or belts in order that the parts may properly perform 10 their operations relative to each other. 2 is a form over which the sheet material is drawn and guided and about which the sides of the sheet material are bent to form a tubular member which is being fed into 15 other parts of the machine. The form 2 is supported at the rear end of the machine and so that the form 2 will extend into the tubular member. The rear end of the form is secured to the bracket 3 which is suitably 20 bolted to the frame 1 of the machine. Means is provided for feeding a cementitious material to one of the edges of the paper so that when the sides of the paper are turned under the form 2 and the edges come 25 in contact one above the other and are pressed by suitable rollers, such as the rollers 4, the edges of the paper will be secured together to form the tube of paper into which the form 2 extends.

30 The form 2 on the under side thereof is provided with a channel 5 in which is located a rod 6. The rod 6 is pivotally connected to a sliding block 7 that is guided by the channel 5. The rod 6 is pivotally secured 35 in the block 7 by means of suitable nuts 8. The rod 6 and consequently the block 7 is also guided in its movements by the block 9 which is secured by suitable bolts in the channel 5. The rod 6 is provided 40 with a slot 10. The slot 10 has a bend, as at 11, so as to cause the slot to extend 90° around the rod 6, for the purpose of causing the rod 6 to turn on its axis in the block 7, an angle of 90° as and for the purpose 45 hereinafter described. To coact with the slot 10 to produce the turning movement of the rod 6, the block 9 is provided with a pin 12 that extends into the slot 10. The pin 12 is locked in position by means of the nut 50 13 to securely hold the pin 12 in its adjusted position and to prevent binding on the rod 6. Reciprocatory movements of the rod 6 in the block 9 will cause the rod 6 to rotate when the portion 11 of the slot 10 reaches 55 the pin 12.

A rod 14 is adjustably connected to the end of the rod 6, the rod 14 being threaded into the end of the rod 6. It is secured in its adjusted position with reference to the rod 60 6 by means of the nut 15. The form 2 has an extension 16 which is bolted to the end of the form 2. The extension of the form 2 is bored centrally to form a bearing for the rod 14. The end of the rod 14 is provided 65 with a flattened portion 17. This may

be formed by bending the end of the rod 14 back. This leaves one side of the portion 17 in line with the side of the rod while the other side of the portion 17 is inclined away from the body portion of the rod. The slot 70 10 is so formed that the rod is held normally so that the flat portion 17 lies in a horizontal plane and until the portion 11 of the slot 10 passes along the inner end of the pin 12 whereupon the rod 14 is rotated 75 so as to cause the flattened portion to stand its edge. The flattened portion 17 rolls on the side of the flattened portion which is in line with the body portion of the rod thus causing the inclined edge of the flattened portion 17 to be turned upward when the end of the pin 12 is in the following end 80 of the slot 10.

The reciprocatory movement of the rods 6 and 14 is accomplished by means of the 85 arm 18 which is connected by a link 19 to the block 7. The arm 18 may be operated by any suitable means. In the construction shown, a reciprocatory rod 20 operates upon an arm 21 which is keyed to a shaft 22 to 90 which the arm 18 is keyed. The arm 20 is operated by a cam 23 located on the shaft 24. The cam 23 has a slot 25 in which is located a roller 26 that causes the rod 20 to reciprocate vertically and thus swing the 95 arm 18.

The movements of the rod 14 is timed with reference to the operations of the cutter bar 27 which severs portions of the tubular member formed on the form 2. The rod 14 100 follows the cutter bar 27 immediately after its operation to cut the paper and thus it follows very closely the forward edge of the tubular member as it advances through the machine. The rod thus passes beneath 105 the cutter bar while the cutter bar is being raised.

The cutter bar is connected to a pair of pins 28 located in disks 29 connected to or forming a part of a shaft 30 which may 110 be operated in any suitable manner to cause rotation of the cutter bar but in unison with movements of the rod 14 which is operated by the arm 18. In the form of structure shown the cutter bar 27 is rotated by a gear 115 operated by the shaft 24 to which the rod 14 is connected through mechanism heretofore described. The disks 29 are provided with pivoted arms 31 that extend over the pins 28. The arms 31 are operated upon 120 by rollers 32 located on the frame of the machine and so as to depress the pins 28 and consequently to force the cutter bar 21 down. Compression springs 33 surround the pins 28 and cause the return of the pins 125 28 after the arms 31 have passed from beneath the rollers 32. By this arrangement there will be a quick downward movement of the cutter bar when the edge of the knife is pointed downward.

A channel bar 34 coacts with the cutter bar 27 to sever the paper. The channel bar 34 is supported in arms 35 that are located upon a shaft 36. The shafts 30 and 36 are connected together by gear wheels 37 and 38 and so that when the cutter bar 27 is forced downward by the operation of the cam rollers 32 the cutter bar will enter the channel bar 34. The channel 39 of the channel bar 34 is provided with sides 40 that incline inward, the top of the channel being narrower than the bottom of the channel. This permits the very slight angular movement of the cutter blade 27 with respect to the channel bar while the edge of the cutter blade is within the channel. This angular movement is performed while the cutter blade is entering and receding from the channel bar during the cutting operation.

To prevent sticking of the paper to the blade, a narrow spring pressed plate or bar 41 may be supported in the vicinity of the cutter bar 27 on the following side thereof which will act as a pressure foot to keep the paper down on the return or lifting movement of the cutter bar 27. Immediately after the cutting operation the end of the rod 14 follows close to the cutter bar 27 as it is rotated forward and upward so as to follow closely the edge of the tubular member formed on the form 2. It follows the edge to the folding means of the machine.

The folding means of the machine consists of a shoe 42, a shoe-plate 43 and a movable folding bar 44. The shoe 42 is supported on an overhanging part of the frame 1. The shoe-plate 43 is bolted to the lower side of the shoe 42 and in proximity to the bed of the machine. The shoe-plate lies parallel to the bed of the machine and in proximity thereto but sufficiently distant therefrom to permit the movement of the folder bar 44 beneath the plate and also to permit the bar to drag the end of the tubular member beneath the plate 43. The point 45 of the shoe is located on the following side, that is, it is located so as to receive the forward end of the tubular member formed of the paper. The rod 14 follows the end of the tubular member until it comes in proximity to the point 45 of the shoe 42 whereupon the rod 46 is rotated so as to lift one side edge of the end of the tubular member above the toe of the shoe and to hold the other side edge below the plate 43. Further forward movement of the paper by the operation of the rollers 45 will cause the upper side edge to slide up onto the shoe and the lower side edge to pass beneath the plate 43. The instant that the side edges of the paper have been so guided that further proper movement of the ends of the sides of the paper tube are

secured, the rod 14 is withdrawn to avoid engagement with the folding bar 44. The folding bar 44 is located in a pair of blocks 47 to which may be connected a pair of rollers 48 that move in side channel bars 49. The channel bars 49 are secured to the frame 1 and extend along the sides of the machine. They extend upward from the bed plate of the machine. The blocks 47 are connected by links 50 to arms 51 which are secured to the shaft 52. Angular movements of the arms 51 causes movement of the blocks 47 along the channel 53 of the channel bars 49 and consequently causes the folding bar 44 to move to and from 80 and along the bed plate of the machine. The channel bars 49 are so located that the folding bar 44 is raised above the bed plate of the machine on the following side of the shoe 42 and so as to permit the end 85 of the paper tube to pass to the shoe 42. During the time that the folding bar 44 is thus held above the bed plate of the machine the end of the rod 14 passes beneath the folding bar together with the end of 90 the paper tube and the bar 14 is rotated so as to lift the upper side edge of the paper above the toe or point of the shoe 42 and when the paper has been properly directed the bar 14 is rotated back and at 95 the same time is withdrawn from the end of the paper tube and also from beneath the folding bar 44 and the cutter bar 27. Immediately upon withdrawal of the end 100 of the bar 14 from beneath the folding bar 44 the arms 51 are swung forward to draw the folding bar beneath the plate 43. This engages the upper side of the paper 60 near the end thereof so as to draw the end of the paper tube beneath the folding plate 105 43 and in so doing the upper side end portion of the paper tube will be folded back on the body portion of the paper 60. Further operations are performed in the formation of the bag, which, however, form no 110 part of the invention presented in this application. Immediately upon the withdrawal of the end of the rod 14 from beneath the cutter bar 27 the paper is severed and the severed portion passes from beneath the shoe and folding plate to other parts of the machine that perform the operations required to complete the bag. The end of the paper tube again advances while the cutter bar 27 is raised and the folding 120 bar 44 returns to its position behind the shoe 42, that is, on the following side of the shoe 42 and to a point well above the bed of the machine. The operations thus repeat themselves, the end of the rod 14 following the side edges of the tube of paper until they are properly directed with reference to the shoe 42 and the plate 43.

The arm 51 that is connected to the folding bar 44 may be operated by any suitable 130

means. In the construction shown the arm 51 is operated by a reciprocating bar 54 which is operated by a cam wheel 55 having a cam slot 56 in which is located a roller 57 that is attached to the bar 54. Rotation of the cam wheel 55 causes oscillating movements of the arms 51. The shaft 52 may be operated by any suitable means so that it will be properly timed with reference to the movements of the cutter bar 27 and the rod 14. It may be connected to the gears 37 and 38 by means of the gear wheel 58.

We claim:

- 15 1. In a bag making machine, a means for forming a tubular member, a means for folding the end of the tubular member, and means for positively separating end edges of the sides of the tubular member for certain engagement of the tubular member by the folding means.
- 20 2. In a bag making machine, a means for forming a tubular member, a means for folding the end of the tubular member, a 25 rotatable member for directing the side edges with reference to the folding means.
- 30 3. In a bag forming machine, a shoe for folding side edges of a tubular member, a rotatable member for directing the side edges of the end of the tubular member to direct one side edge above the point of the shoe and the other side edge below the point of the shoe.
- 35 4. In a bag making machine, a means for forming a tubular member, means for folding the end of the tubular member, means for severing end portions of the tubular member, a rod extending through the tubular member, means for causing reciprocating movements of the rod to cause the rod to follow the end of the tubular member to the folding means and beneath the severing means, and means located on the rod to positively guide the side edges of the end of the tubular member with reference to the folding means.
- 50 5. In a bag making machine, means for forming a tubular member, a shoe for engaging the end of the tubular member for purposes of folding the end of the tubular member, a rotatable rod having a flat end portion, means for causing reciprocating movements of the rod to cause the rod to follow the forward end of the tubular member to the shoe and to rotate the rod to raise one side edge of the tubular member above the shoe point and to direct the lower side

edge of the tubular member below the point of the shoe.

6. In a bag forming machine, a means for forming a tubular member, a shoe, a folding bar, means for causing the folding bar to engage the end of the tubular member and pass beneath the shoe to fold the end of the tubular member, a rotatable rod having a flattened portion at its end, means for reciprocating the rod to cause the rod to follow the end edges of the tubular member beneath the folding bar and to the point of the shoe and to rotate the bar to raise the upper side edge above the shoe and to direct the lower side edge beneath the shoe and to withdraw the rod from beneath the folding bar.

7. In a bag forming machine, a means for forming a tubular member, a shoe, a folding bar, means for causing the folding bar to engage the end of the tubular member and pass beneath the shoe to fold the end of the tubular member, a severing means for severing end portions of the tubular member, a rotatable rod having a flattened portion at its end, means for reciprocating the rod to cause the rod to follow the end edges of the tubular member beneath the folding bar and to the point of the shoe and to rotate the rod to raise the upper side edge above the shoe and to direct the lower side edge beneath the shoe and to withdraw the rod from beneath the folding bar, and from beneath the severing means.

8. In a bag forming machine, means for forming a tubular member, a shoe and a folding bar, means for operating the folding bar to engage the end of the upper side of the tubular member and to fold it back on the body portion of the tubular member, a severing means for severing the end portions of the tubular member, a rotatable rod having an end portion extending angularly away from the body portion of the rod, means for causing reciprocating movements of the rod to cause the end portion to follow the end edge of the tubular member to the shoe, the rod having a channel extending along the body portion of the rod and turned 90° at the following end of the rod, a pin extending into the channel for causing rotation of the rod when the end of the rod comes in proximity to the point of the shoe.

In testimony whereof we have hereunto signed our names to this specification.

LOUIS H. HARTMAN.
CARL H. HARTMAN.
